UNITED STATES PATENT OFFICE

CHARLES F. KOLB, OF CHICAGO, ILLINOIS

DOOR BED

Application filed June 27, 1924. Serial No. 722,663.

This invention relates to improvements in door beds and consists of the matters herein-after described and more particularly pointed out in the appended claim.

5 One of the objects of the present invention is to so support a comparatively wide bed upon a narrower, swinging door, that the bed may be shifted laterally upon the door to permit said bed to clear and pass through the 10 door opening when the door is swung into position to conceal the bed from view.

Another object of the invention is to provide a novel and improved arrangement of 15 two co-acting doors, upon one of which is supported a wider bed, so that when the door supporting the bed has been swung into a position normally occupied by the other door, said other door may be swung into the position normally occupied by the first mentioned 20 door, and may thereafter be used as an entrance or service door in passing from the bed room into the dressing room or other compartment in which the bed has been concealed.

25 A further object of the invention is to provide improved co-acting parts on the bed and door respectively, which not only permit of an easy lateral shifting or movement of the bed with respect to the associated door, but 30 will hold the bed against sagging downward.

These objects of the invention, as well as the many advantages thereof, will more fully appear as I proceed with my specification.

In the drawings:

35 Fig. 1 is a perspective view of a door bed embodying my invention as it appears when the frame thereof is in the extended horizontal position.

Fig. 2 is a view in side elevation of the 40 frame of my improved door bed, with the associated door shown in vertical section.

Fig. 3 is a vertical sectional view as taken on the line 3—3 of Fig. 2.

45 Figs. 4—6 and 7 are diagrammatic horizontal sectional views on a reduced scale, showing the manner of operation, in moving the bed from the sleeping room into an adjacent dressing room or other compartment.

50 Referring now in detail to that embodiment of the invention illustrated in the ac-

companying drawings:—10 indicates one of the walls of a house or other building, which separates two rooms or other compartments thereof from each other. In said wall is a 55 passageway or door opening 11, which is normally closed, preferably by two doors 12 and 13 respectively. Said doors are pivoted to swing about a common axis provided by pins 14 and 15 respectively which are mounted in the wall 10 and floor 16 and are operatively connected with the adjacent edges of the said doors as shown in Figs. 1 and 3.

60 On one side of the door 12 at its bottom end is provided two horizontally spaced, outstanding bearing brackets 17—17 each of 65 which carries an anti-friction device or roller 18—18 which turns about a vertical axis. Spaced a suitable distance above the rollers 18—18 are grooved rollers 19—19 which are journaled upon horizontally outstanding pins carried by brackets 20—20 secured to the door in any suitable manner, in the vertical planes of the brackets 17. On said door, between and a short distance above the rollers 19—19, is a third roller 21 journaled on a 70 bracket 22 secured to said door. The door 12 provides a swinging support for a foldable bed frame, so that it may be moved from a position for use on one side of the wall 10, through the door opening 11, to a concealed 75 position on the other side of said wall as will 80 later appear.

The bed frame comprises a head frame 23, a foot frame 24 and a body frame which includes parallel side bars 25 and parallel end 85 bars 26 respectively. The head frame includes an inverted U-shaped member having upright side posts or legs 27 and an integral horizontal top member 28, all preferably made of a rectangular metallic tubing. The 90 posts or legs 27 of the head frame are connected together by a flat bar 29 near the bottom ends thereof, and by a channel bar 30, spaced a suitable distance above the bar 29, 95 said channel bar being arranged with its flange facing downwardly. As will later appear said bars 29 and 30 which are located on the back of the head frame, co-act with the rollers 18 and 19 and 21 respectively, before mentioned to provide not only a detachable 100

connection between the bed and door, but also for a lateral relative movement between the bed and door 12.

The foot frame 24 of the bed is fixed to the 5 end of the body frame provided by the side and end bars 25 and 26, and pivoted to the foot end of the body frame are hinged or folding legs 31 which form in effect, when the bed is in its position for use, continuations of 10 the side members of the foot frame. The head end of the body frame side bars 25—25 are bent upwardly in the plane of the head frame to provide short arms 32—32, which include short horizontal extensions, each carrying a roller 33 which is adapted for rolling contact with the rear sides of the posts or legs 27 of the head frame.

34—34 indicate brace or fulcrum bars each of which includes two arms 35 and 36 respectively arranged at substantially a right angle to each other. The arms 35 are pivotally connected to the bottom ends of the posts 27 of the head frame, said bottom ends like the folding legs 31 before mentioned clearing, or 20 being spaced above the floor 16. The bars 34 are each pivoted at the junction between the arms 35—36 to the side bars 25—25 of the body frame at points spaced from the head frame 23 and the other arms 36 extend upwardly and rearwardly toward the head frame 23 and terminate in laterally and inwardly bent fingers 37—37. Said fingers are adapted when the bed frame is being folded 30 upwardly to bear upon the mattress and pillows on said bed frame so that they cannot shift or slip when the bed is in its final folded position.

As shown herein, the bed frame is considerably wider than the door 12 with which it is 40 associated. When the channel bar 30 on the head frame 23 is engaged upon the rollers 19 and under the roller 21 on the door, the flat bar 29 at the bottom of the head frame bears with a thrust under the weight of the bed 45 frame against the rollers 18—18, so that the bed frame may be shifted laterally of the door. As is apparent, said door bears the entire weight of the bed and thus provides a support therefor which may be swung about 50 the common axis provided by the pins 14 and 15.

Assume that the parts are all in the position shown in Fig. 1 wherein the bed is on one side of the wall 10 and is down in its horizontal position ready for use. Should it be desired to sweep or otherwise clean under the bed while it is in this position, it is only necessary to shift the same laterally of the door 12 toward the door 13, thus giving unobstructed access to that part of the floor normally under the bed.

When it is desired to conceal the bed from view, the foot end 24 thereof is lifted upwardly so that the bed stands in the vertical 65 folded position shown in dotted lines in Fig.

2. In this folding up movement of the bed, the rollers 33 travel downwardly along the back face of the posts 27 of the head frame and the fulcrum or brace links 34 swing in a short arc into the position shown in Fig. 2. Suitable mechanism (not shown herein as it forms no specific part of this invention) is employed in the operative connection between the head and bed frame so that the said bed frame is counter-balanced and will not fall or swing down from the folded position under its own weight. The folded bed may be shifted laterally of the door 12, by means of the bars or rails and rollers before mentioned until its left hand side (as viewed in the drawings) is free of or clears the left hand side of the door opening 11 as indicated in dotted lines in Fig. 3 and as shown in the diagrammatic view in Fig. 5.

The door 12 may now be swung about the 85 common axis of both doors to stand in a plane at a right angle to said wall 10, after which the door 13 is then swung into a position opposite that of said door 12 as shown in dotted lines in Fig. 6. The doors 12 and 13 90 may then be swung into the full line positions shown in Fig. 7; said doors in this instance being relatively interchanged with the bed concealed behind or back of the other side of the wall 10. The door 13 may be used as 95 the service door in passing through the door opening no matter whether it is in the right hand or left hand side of door opening.

In the folding movement of the bed frame the fingers 37 of the fulcrum or brace bars are caused to bear down upon the pillows and mattress so as to hold them in position on the bed frame after the same has been folded upwardly. When the bed is in a position ready for use, the laterally extending 100 fingers of said fulcrum bars assume a position near the head end of the mattress and are concealed by the pillows which are placed near the head end of the bed, said laterally extending fingers being out of the way when 105 the bed is in actual use.

The rails and rollers providing the connection between the door 12 and head frame 23 are so positioned as to be concealed when the bed is down ready for use. Furthermore, said connection is such that the bed frame may be easily removed as an entirety from the door 12, should it so be necessary.

By use of the roller 21 which engages upon the top surface of the channel 30, the bed 110 cannot tip laterally in either direction, under the weight of a person occupying one or the other side of the bed.

While in describing my invention I have referred to the same as a door bed and have 115 illustrated and described the same as such, but I do not wish to be limited to beds mounted on doors alone, as the invention may be used in connection with beds mounted on fixed supports such as a building wall or the 120

invention may be used in connection with folding beds of the cabinet type.

I claim as my invention:—

In a structure of the kind described, the combination of a support and a frame member laterally movable thereon, a pair of spaced apart grooved rollers fixed to the support, a downwardly facing channel member secured to said frame member and having one of its flanges engaged with said grooved rollers, a device on said support between said rollers and engaging with the top web of said channel member for holding the frame member against lateral tipping, and means on said support and frame member respectively near the bottom ends providing a thrust receiving bearing between said support and frame member.

In testimony that I claim the foregoing as my invention, I affix my signature, this 15th day of May, A. D. 1924.

CHARLES F. KOLB.
